UNITED STATES PATENT OFFICE.

MARTHA POSTLEWAIT, OF DENVER, COLORADO, ASSIGNOR OF ONE-HALF TO HENRY ROY SPANGLER, OF DENVER, COLORADO.

HAIR CURLER.

Application filed May 13, 1927. Serial No. 191,170.

The invention relates to improvements in hair curlers of the type in which an elongated core (preferably a clamp) is provided, around which to wind the hair, and in which 5 a pivoted clamping member is employed to hold the wound hair upon the core, the principal object of the invention being to provide new and improved means for holding said pivoted clamping member in operative position.

A further aim is to provide a hair curler of extreme simplicity and hence one which may be inexpensively manufactured and sold at small cost.

With the foregoing in view, the invention resides in the novel subject matter herein-after described and claimed, the description being supplemented by the accompanying drawing.

Fig. 1 is a perspective view showing the curler open in readiness for engagement with a lock of hair.

Fig. 2 is a perspective view showing the hair ends clamped in the core.

Fig. 3 is a perspective view illustrating the curler secured in operative position upon the wound hair.

Fig. 4 is an end elevation.

Fig. 5 is a perspective view of the clamping member which secures the wound hair upon the core.

In the drawings above briefly described, the preferred form of construction has been illustrated, and while this construction will be herein specifically described, it is to be understood that within the scope of the invention as claimed, variations may be made.

C denotes a core of elongated form, around which to wind a lock of hair H, and C' denotes a clamping member for holding the wound hair upon the core. This clamping member has one of its ends pivoted to the core C while at its other end, said clamping member is provided with spaced lateral fingers 6 to straddle the core as shown in Figs. 3 and 4, for the purpose of holding the clamping member and the core in operative relation, either of said fingers being releasable from engagement with the core to permit the clamping member C' to swing to an inoperative position, so that the core may be withdrawn from the curled hair.

Preferably, the core C is in the form of a clamp consisting of two spring metal jaws 7 covered by yieldable sleeves 8, connected at

one end by an integral loop 9, and provided at their other ends with co-acting connecting means 10-11.

The clamping member C' herein shown, is formed from a single length of resilient wire bent to provide two parallel arms 12 and a transverse portion 13 connecting said arms at one end, said transverse portion 13 being rotatably received in the loop 9 and being provided with spacing sleeves 14 between said loop and said arms. The free ends of the arms 12 are given two right-angular bends to provide the inwardly projecting lateral fingers 6, and the free ends of these fingers are preferably provided with enlarged rounded terminals 15.

In using the device on bobbed hair, the free end of a lock of the hair is clamped between the jaws 7 and with the clamping member C' substantially in alignment with the core C, the entire device is rotated to wind the lock of hair about the core as seen in Fig. 3. Then, the clamping member C' is swung in either direction to dispose its arms 12 against the wound hair, and by springing one or the other of these arms outwardly to a sufficient extent, the fingers 6 may be positioned to straddle the core C as shown in Figs. 3 and 4, thus effectively holding the device in operative relation with the hair.

When using the device on long hair, the core C may or may not be clamped to a lock of the hair either adjacent to the scalp or at other desired points, and the portion of the hair between the core and the free end of the lock is then wound around said core, after which the clamping member C' is fastened in place.

The device is exceptionally simple and inexpensive, may therefore be manufactured at little expense and sold at small cost, yet it will be very desirable and efficient, particular attention being invited to the novel manner of securing the clamping member C' in place, as the construction provided for this purpose, is such that it may be readily applied or released, even on portions of the head which cannot readily be seen, when looking into a mirror.

I claim:—

1. A hair curler comprising an elongated core around which to wind a lock of hair, and resilient hair clamping means extending longitudinally of said core and at one end

pivoted thereto, the other end of said hair clamping means having a pair of spaced lateral fingers to straddle the core and hold said core and means in operative relation, said fingers being releasable from the core by lateral springing of said clamping means.

2. A hair curler comprising an elongated core around which to wind a lock of hair, and a pair of spring arms extending longitudinally of said core and pivoted at one end thereto, the other ends of said arms being provided with lateral fingers to straddle the core and releasably hold said arms and core in clamping relation with the wound hair.

3. A hair curler comprising two elongated

hair-clamping jaws connected at one end by a loop and provided with releasable connecting means at their free ends for holding them in closed position, and a 20 length of resilient wire bent to provide two parallel hair-clamping arms and a transverse portion connecting them; said transverse portion being rotatably received in said loop, the free ends of said arms being bent to provide spaced lateral fingers adapted to straddle the free ends of the aforesaid jaws when the latter are held in closed position.

In testimony whereof I have hereunto affixed my signature.

MARTHA POSTLEWAIT.
